United States Patent Office

Des. 203,942
Patented Mar. 1, 1966

203,942

CUP HOLDER

Bertrand N. Trombley, Bloomfield Hills, Mich., assignor to The Dow Chemical Company, Midland, Mich., a corporation of Delaware

Filed Aug. 26, 1964, Ser. No. 81,451

Term of patent 14 years

(Cl. D44—10)

Fig. 4

I claim:

The ornamental design for a cup holder, substantially as shown and described.
